(57) **CLAIM**

The ornamental design for a pool table, as shown and described.

DESCRIPTION

FIG. 1 is top perspective view of a pool table showing my new design;

FIG. 2 is a top plan view thereof;

FIG. 3 is a rear elevational view thereof;

FIG. 4 is a rear elevational view thereof; and,

FIG. 5 is a side elevational view thereof, rotated 60 degrees of FIG. 3.

The broken lines are for illustrative purpose only and form no part of the claimed design.
